UNITED STATES PATENT OFFICE.

RALPH H. ROSE, OF DETROIT, MICHIGAN.

BURGLAR AND FIRE ALARM SIGNAL FOR TELEPHONES.

Application filed August 25, 1921. Serial No. 495,225.

To all whom it may concern:

Be it known that I, RALPH H. ROSE, a citizen of the United States, residing at Detroit, in the county of Wayne and State 5 of Michigan, have invented certain new and useful Improvements in Burglar and Fire Alarm Signals for Telephones; and I hereby declare that the following is a full, clear, and exact description thereof, reference 10 being had to the accompanying drawings, which form part of this specification.

This invention relates to burglar and fire alarm apparatus. The present invention has special reference to an attachment whereby 15 an audible signal is automatically transmitted through the ordinary telephone, in case of burglary or fire, and the device may be used in connection with an ordinary desk telephone apparatus and in connection with 20 any electric burglar alarm or electric fire alarm system. By this invention an alarm will be automatically telephoned to "central" or to a police station through the ordinary telephone apparatus in case an electric 25 burglar alarm circuit is closed by a burglarious entrance into a building equipped therewith or in case an automatic electric fire alarm circuit is closed by fire breaking out in a building equipped therewith. In 30 particular the invention is designed for use in connection with the burglar and fire alarm apparatus shown in my application filed July 25th, 1921, Serial No. 487,250, but it may be readily used in connection 35 with other electrical burglar alarm systems and other electrical fire alarm systems and with the ordinary desk telephone receiving and transmitting apparatus.

The object of the invention is to provide 40 a novel apparatus adapted to be connected in with a burglar alarm circuit or fire alarm circuit and to be placed on a table or desk beside the ordinary telephone apparatus, and adapted, in case a circuit is closed 45 through the burglar alarm system, or fire alarm system, to elevate the telephone arm and to audibly notify "central" of the burglary or fire; by automatically transmitting through the telephone an audible 50 signal calling attention to the trouble and the location thereof; the signal being continued or repeated sufficiently long to insure that "central" or "police" shall be fully informed of the situation.

55 A further object of the invention is to

provide the apparatus with a phonograph whereby when the apparatus is operated the location of the trouble and desired assistance will be called orally into the telephone receiver by the phonograph a sufficient number of times to insure "central" fully understanding the nature and location of the trouble.

If desired, instead of connecting the wire with "central" it may be transmitted directly to police headquarters; or both "central" and police could be notified through proper connections by the same apparatus.

I will explain apparatus embodying the invention, and illustrate in the accompanying drawings, to enable others to understand and use the same. The invention, however, is not restricted to the particular form of apparatus shown in the drawings, as it is capable of embodiment in various 75 forms within the scope of the invention, and therefore I refer to the claims for summaries of the essentials of the invention, and of the novel features of construction and novel combination of parts for all of which 80 protection is desired.

In said drawings:

Fig. 1 is a view of the apparatus in position beside an ordinary telephone receiving and transmitting apparatus.

Fig. 2 is an enlarged horizontal section through the apparatus with phonographic audible signal and bell alarm attachment; and also shows diagrammatically the electrical connections between a fire or burglar 90 alarm system and the said device.

Fig. 3 is a sectional view on the line 3—3, Fig. 2.

Fig. 4 is a similar section on line 4—4, Fig. 2.

Fig. 5 is a sectional view of an apparatus having only an audible bell signal, and illustrates diagrammatically the electric connections of such apparatus with a burglar or fire alarm system.

The apparatus comprises a casing 1, which may be of any suitable material and of sufficient size to contain the working parts.

In this casing is a lever 2 which may be pivoted in any suitable manner, as at 2^a on the side of the casing, and one end of this lever projects out of the casing through an opening or slot in the front thereof. The lever 2 is normally held in depressed or substantially horizontal position as indicated in 110

Fig. 4, but may be moved when released, by suitably arranged spring means, so as to elevate its outer end, as shown in dotted lines in Fig. 4. As shown a contractile 5 spring 2^b is attached to the lever and to the bottom of the casing. The inner end of the lever 2 is normally upheld by a trip lever or catch 3, which has a finger 3^c on its upper end adapted to underlie the inner end 10 of the lever 2. The lever 3 may be pivoted at 3^b to the side of the casing. The lower end of lever 3 is shown as pivotally connected by a rod or link 3^e to one end of the core 4^a of a solenoid 4.

15 The solenoid 4 is mounted in the casing adjacent the lower end of trip lever 3. The core 4^a is normally retracted by a spring 4^f as indicated in Fig. 3, so as to hold the finger 3^a under the lever 2. The opposite 20 terminals of the solenoid 4 are connected by suitable wirings to a fire or burglar alarm circuit as hereinafter explained, or in other suitable manner.

The construction is such that when the 25 fire alarm or burglar alarm circuit is closed a circuit will be also closed through the solenoid 4, which will thereupon cause the core 4^a to move and rock the lever 3 so that finger 3^c releases lever 2, whereupon spring 30 2^b depresses the inner end of lever 2 and the outer end thereof is raised and elevates the telephone receiver, as hereinafter explained.

35 Mounted in the casing 1 is an audible signal whose sound is to be transmitted through the telephone transmitter when the lever 2 is released. The audible signal may be a bell or a phonograph or both. In the form shown in Figs. 1 to 4 a phonograph audible signal is used.

40 As shown the phonograph signal comprises an ordinary phonograph record 5, which may be of any suitable construction, and is shown as a disk record 5, and may 45 be operated when released, by any suitable spring motor mechanism or any suitable electric motor mechanism (not shown). The particular motor means for operating such phonograph record forms no part of 50 the present invention.

The disk 5 should have a suitable record made thereon to give the desired information to central or police headquarters, with which the telephone is connected. Such 55 record could be made to call attention to fire or burglary or both and give the location and address of the house and place where the burglary or fire occurred, and this record should be repeated a number of times 60 on the disk to insure that central would get the correct information and give the desired alarm to the police or fireman.

65 Cooperating with this disk 5 is a reproducer 5^e which may be of any suitable ordinary construction mounted on a swing-

able horn 5^b of any suitable construction, and which connects with a tube 5^c the mouth of which connects with an opening 1^e in the front side of the casing 1 adjacent the projecting end of the lever 2.

70 A stop device 5^e of any suitable construction (preferably such as is commonly employed) is provided to normally prevent rotation of the disk 5. As shown in Fig. 2 this stop device is controlled by a lever 5^e 75 pivoted beside the disk and having a member 5^f that prevents rotation of the disk 5 when the lever 2 is in normal position. A spring 5^g may be provided to normally hold the stop lever 5^e in position to arrest the 80 disk 5.

The lever 5^e is shown as connected to one end of a cord 5^h which runs over a pulley 5ⁱ and is attached to the inner end of the lever 2 as indicated in Figs. 2 and 4 and when the 85 lever 2 is released and its inner end is depressed by the spring 2^b the cord 5^h causes lever 5^e to release the disk 5, and the latter will begin to turn, and the record thereon will be audibly reproduced and transmitted 90 through the opening 1^e.

An audible signal such as an electric bell 6 may be arranged in the casing 1 and one post of this bell may be connected by a wire 6^a to a metal plate 2ⁿ attached to the lever 2, 95 and the other post of this bell may be connected by a wire 6^w to one pole of a source of electricity 3^y (see Figs. 2 and 4). When the lever 2 is released the inner end of the plate 2ⁿ is adapted to make electrical contact 100 with a member 6^c in the casing connected by a wire 6^y to the other pole of the source of electricity 3^y; so that when the lever 2 is dropped an electrical circuit will be closed through the bell and the latter will be 105 sounded.

The casing 1 is preferably made of such size that when placed upon a table or stand the ordinary combination telephone transmitting and receiving apparatus (indicated in 110 dotted lines in Figs. 1 and 2) can be placed beside the casing so that the arm of the telephone apparatus on which the receiver R is usually hung will overlie the projecting end of the lever 2, (when the latter is in 115 normal position and locked by the trip lever 3) and may rest in a notch 2^s in the end of the lever 2 as indicated in the drawing; while the mouth of the transmitter T of the 120 telephone apparatus will be placed directly against the casing and cover the opening 1^e as indicated in Figs. 1 and 2.

125 The terminals of the solenoid 4 are preferably connected by wires 4^w, 4^x respectively to the wires of the burglar alarm or fire alarm circuit. In the drawings I have indicated the wires 4^w, 4^x as being connected with a burglar and fire alarm apparatus such as disclosed in my co-pending application for patent on burglar and 130

fire alarm filed July 25, 1921, Serial No. 487,250. In said apparatus a circuit will be closed from a source of electricity 3^y through the alarm bell 5^y, 5^z as indicated in the drawing and through other visual signal devices (not shown) set forth in said application but unnecessary to describe herein. The electric circuits can be readily traced on the drawings.

- 10 Preferably the wires 4^w, 4^x are provided with the usual disconnectible plug and socket (see Figs. 2 and 5) and the wires 6^t, 6^y are provided with a usual disconnectible plug and socket 6^z (in Figs. 2 and 5) so that if it is desired to remove the casing 1 from the telephone apparatus, it can be readily done by disconnecting the plugs from the sockets; and it can be readily replaced and connected in the circuit when desired.
- 15 Fig. 5 shows a simple form of apparatus in which only an alarm bell 6 is employed; the electrical connections being diagrammatically illustrated therein.

As shown in the drawings the wire 4^w is connected to the positive wire 3^a of the burglar or electric alarm circuit and the wire 4^x is connected to the negative wire 5^a between the switch 5^x and the source of electricity 3^y. The signal bell 5^y is connected to one terminal of the source of electricity 3^y by the wire 5^t which connects through switch 5^x with wire 5^a, and also connects by wires 3^t and 3^a with the other terminal of the source of electricity. The burglar and fire alarm systems however may be of any desired construction. When by raising a window a burglar alarm circuit is closed, (or if when a fire is started the fire alarm circuit is closed) the wire 3^a and the closed switch 5^x forms part of such circuit the bell 5^y will be rung and at the same time an electric circuit will be closed through the solenoid 4, and when energized this solenoid causes core 4^a to move catch lever 3 and finger 3^a releases lever 2, which is immediately moved by the spring 2^b into the position (indicated in dotted lines in Figure 2), closing contact through the bell circuit 6, which will ring an alarm in the casing 1; and the same movement of the lever 2 through the cord 5^h, or connections causes the stop lever 5^e to release the disk 5, which moves and sounds an oral alarm which is transmitted through the telephone transmitter.

55 If the burglar alarm circuit should then be broken by the burglar closing the window or door the bell 5^y, 5^z would cease to ring (as explained in my said application) but the lever 2 being held down by the spring the audible signals would continue to be transmitted by the phonograph through the telephone transmitter and the circuit through the bell 6 would remain closed until the signaling is stopped by some person elevating the receiver and resetting the lever 2.

The leads to the solenoid 4 and the bell 6 may be broken or placed in the circuit as desired by means of the plug and socket connections 4^w, and 6^z, and the bell 5^y may be thrown into or out of circuit by opening switch 5^x.

Where the phonograph audible signal is used the bell may be dispensed with; or the bell could be located at some place in the electrical circuit 6^v—6^w where it would not interfere with the phonograph transmission. In other words in some cases the phonograph might be omitted and only the bell used; or in some cases the bell may be omitted and only the phonograph used, or in some cases both may be used.

When a burglar alarm circuit is closed (or a fire alarm circuit is closed) as described in my aforesaid application, the lever 2 is automatically released, the telephone transmitter arm automatically raised starting the phonograph and summoning the police or fireman through the telephone as above described; also if desired giving an audible local alarm or bell signal.

If desired the casing might contain two phonographic devices one for a burglar alarm and one for a fire alarm; one phonograph being in circuit with the burglar alarm system and adapted to give an alarm as above described when the burglar system circuit is closed; and the other being connected with the fire alarm circuit so that if such circuit is closed the fire alarm will be operated as above described. If both circuits are closed both phonographs will be operated. The extension horns from both the phonographs could connect with the same opening in the casing, so that only one telephone apparatus would be required.

In the drawings I have only indicated the connections for the bells, a source of electricity, and switch 5^x, of the burglar and fire alarm shown in my aforesaid application that being sufficient to enable the present invention to be clearly understood.

The phonograph may be operated by a spring motor (not shown) adapted to be wound by hand as usual only the winding handle being indicated in the drawing, as the specific construction of the motor and its operating mechanisms are not part of the present invention.

If an electric motor is used to turn the phonograph disks it could be suitably wired in the circuit in any well known practical way. Any make of phonograph can be used. When the phonograph is once started it will continue to operate or play the record thereon until it runs down or is stopped by some one.

By opening switch 5^x all current would be passed through wire 4^w to telephone alarm fixture and the bells and lights of my aforesaid burglar and fire alarm apparatus appli-

cation would be cut out leaving the signal attachment in operative condition.

What I claim is:

1. In apparatus of the character specified, a casing adjacent an ordinary telephone receiving and transmitting apparatus and having an opening therein registering with the transmitting apparatus; a lever pivoted in the casing and having a portion projecting 5 out of the casing and underlying the hook of the receiving apparatus; an audible signal apparatus within the casing; and means in the casing for normally holding the outer end of said lever depressed, said means being 10 connected in a normally open electric alarm circuit, whereby when said circuit is closed said means is released permitting the receiver hook to raise, and causing an audible signal to be transmitted through the opening 15 in the casing directly into the transmitter apparatus.

2. In apparatus as set forth in claim 1, said audible signal comprising a phonograph within the casing having a horn leading directly 20 to the opening in the side of said casing, and means controlled by said lever whereby said phonograph is held inoperative when the said member is in normal position, and whereby the phonograph is permitted to 25 operate when the said member is released.

3. A signal apparatus, comprising a casing, a lever pivoted in the casing having one end projecting outside of the casing, a spring in the casing for rocking said lever, a pivoted trip for holding the outer end of the lever in normal depressed position, electrical means for causing the trip to release the lever; an audible signal within the casing, means for holding said signal inactive when 30 the lever is in normal position, and for actuating the signal when the lever is released, and connections between the said trip controlling means and a normally open electric alarm circuit; said casing being placed beside 35 an ordinary desk telephone fixture with the projecting end of the lever underlying the telephone receiver hook, whereby when the alarm circuit is closed the said lever is automatically released lifting the telephone receiver and an audible signal will be thereby transmitted directly through the opening in the casing into the telephone transmitter, substantially as described.

4. In an apparatus as set forth in claim 3, said audible signal comprising a phonograph within the casing having a sound conducting horn leading directly to an opening in said casing registering with the telephone transmitter, and means controlled by said lever whereby said phonograph is held inoperative when the said lever is in normal position,

and whereby said phonograph is permitted to operate when the said lever is released.

5. In an apparatus of the character specified, a casing placed beside an ordinary desk telephone fixture; a lever pivoted in the casing, and having one end projecting out of the casing and adapted to underlie the telephone receiver hook when said lever is in normal position; a spring in the casing normally tending to raise the projecting end of the lever; a trip in the casing adapted to hold the lever in normal position against the action of said spring, an electromagnet for releasing the trip; a phonograph in the casing having a sound conducting horn registering with the telephone transmitter through an opening in the side of the casing; means connected to said lever for holding the phonograph inactive when the lever is in normal position, and for actuating the phonograph when said lever is released; and electrical connections between the said electromagnet and a normally open electric alarm circuit whereby when the alarm circuit is closed the electromagnet will actuate said trip to release said lever, the telephone receiver will be elevated, and the phonograph will be actuated, to transmit an audible signal through the telephone transmitter, substantially as described.

6. In an apparatus of the character specified, a casing having an opening in one side registering with the transmitter of a telephone apparatus, a lever pivoted in the casing having one end projecting out of the casing and underlying the receiver hook when said lever is in normal position; a spring in the casing tending to raise the projecting end of said lever; a trip in the casing for holding the outer end of the lever in normal depressed position against the action of said spring, an electro-magnet for releasing the trip; a phonograph in the casing having a horn registering directly with the opening in the side of the casing; means for holding the phonograph inactive; a connection between said means and the lever whereby when the phonograph is released the protruding end of the lever is raised; and electrical connections between the said electromagnet and a normally closed electric alarm circuit whereby when said alarm circuit is closed the magnet actuates said trip to release said lever, the telephone receiver is elevated, the phonograph is actuated, and an audible signal is transmitted through the opening in the casing into the telephone transmitter, substantially as described.

In testimony that I claim the foregoing as my own, I affix my signature.

RALPH H. ROSE.
